UNITED STATES PATENT OFFICE.

HARDAMAN B. WEATHERSBY AND JOHN F. BOZEMAN, OF WEST COLUMBIA, TEXAS.

DRILL-ROD TOOL.

Application filed May 17, 1922. Serial No. 561,629.

To all whom it may concern:

Be it known that we, HARDAMAN B. WEATHERSBY and JOHN F. BOZEMAN, citizens of the United States, residing at West Columbia, in the county of Brazoria, State of Texas, have invented certain new and useful Improvements in Drill-Rod Tools; and we do hereby declare the following to be a full, clear, and exact description of the invention, such as will enable others skilled in the art to which it appertains to make and use the same.

This invention relates to new and useful improvements in wrenches and particularly to wrenches adapted for use in connection with well drill rods.

One object of the invention is to provide a wrench of this character by means of which the upper portion of the drill joint 20 may be held against movement while the lower portion is being unscrewed therefrom.

Another object of the invention is to provide a wrench of this character which is simple in construction, formed of few parts, 25 and which can be manufactured at a comparatively low cost.

A further object is to provide a wrench of this character which has a cam gripping jaw face, said jaw face being readily removable for the purpose of replacement when worn or for the application of a different sized jaw face.

Other objects and advantages will be apparent from the following description when taken in consideration with the accompanying drawing.

In the drawing:

Figure 1 is an elevation of a wrench made in accordance with our invention.

Figure 2 is a vertical longitudinal sectional view through the wrench on the line 2—2 of Figure 1.

Figure 3 is a longitudinal central sectional view on the line 3—3 of Figure 2.

Referring particularly to the accompanying drawing, 10 represents a block, having a semi-circular recess 11 in one end and a transverse bifurcated extension 12 at the other end. Formed longitudinally through 50 the block, and opening through the bottom of the recess end 11, and the inner side of the bifurcation 12, is an opening 13. Disposed longitudinally through this opening 13 is a member 14, the head of said member 55 being arcuate as shown at 15, and at each

end of said arcuate portion is a notch or recess 16. Arranged on the arcuate face 15 is an arcuate strip 17, the ends of which are formed with lugs 18, entering the recess 16 and retaining the member 17 on the member 14. This member 17 tapers from one end to the other and has its outer face formed with a longitudinal series of ratchet teeth 19. The end of the member 14, which carries the jaw face 17, is disposed to swing 60 in the opening 13, and project therefrom into the recess 11, as clearly seen in Figures 1 and 3. The other end of the member 14 is in the form of a handle lever 20, and projects beyond the bifurcation 12. A pivot 70 bolt 21 is disposed through the bifurcation and the member 14, whereby said member 14 is pivotally supported within the member 10.

Disposed across the recessed end of the member 10, is an arcuate jaw member 22, one end of which is formed with a reduced apertured lug 23, which enters a recess 24 at one side of the recess 11, and receives therethrough a pivot pin 25. Pivotally supported on a transverse pin 26, disposed through the member 10 at the other side of the recess are the links 27, and pivotally carried by the outer ends of these links is a cam member 28, which is adapted to engage 85 with a shoulder 29, formed on the adjacent end of the member 22, whereby to lock said end of the member 22 against the member 10, in embracing relation to the upper portion of a drill joint.

The pivot bolt 21 has an extension 21' provided with an eye 30 for the reception of a cable or cord for suspending the wrench in the proper position with respect to the drill joint.

When the device is properly engaged around the drill joint and the member 20 is rocked on its pivot so as to bring the thicker end portion of the member 17 into biting engagement with the drill rod joint, 100 this part of the joint will be held stationary while the lower part is being unscrewed therefrom.

What is claimed is:

A pipe turning tool including a ring 105 formed of pivotally connected sections, one of the sections having a bifurcated extension formed centrally on its convex face and lying in the plane of the section, said portion of the section having an arcuate recess com-

municating with the bifurcation, a lever pivoted within the bifurcation and having an enlarged arcuate portion movable in the arcuate recess, the sides of the arcuate portion being formed with recesses, and an arcuate plate disposed on the arcuate face of the lever and having fingers on its ends engaged in said side recesses, said plate being thicker at one end and gradually taper-

ing toward the other end and formed with 10 serrations.

In testimony whereof, we affix our signatures, in the presence of two witnesses.

HARDAMAN B. WEATHERSBY,
JOHN F. BOZEMAN.

Witnesses:

CHARLOTTE E. HARPER,
G. W. DAVIS.
